Primary Examiner — Lucy Lieberman(74) *Attorney, Agent, or Firm* — Patentbar International, P.C.**(57) CLAIM**

The ornamental design for a watch, as shown and described.

DESCRIPTION

FIG. 1 is a front elevation of a watch showing our new design; FIG. 2 is a front and right side perspective view thereof; FIG. 3 is a front and left side perspective view thereof; FIG. 4 is a rear elevation thereof; and, FIG. 5 is a rear and right side perspective view thereof. The broken lines in the drawings are used to show an unclaimed watch band and portions of the watch that do not form part of the claimed design.
